United States Patent Office

Des. 215,322
Patented Sept. 23, 1969

215,322

LAPPING MACHINE

Leonard E. Zerlaut, Santa Ana, Calif., assignor to Conrac
Corporation, Duarte, Calif., a corporation of New York

Filed July 10, 1968, Ser. No. 12,675

Term of patent 14 years

Int. Cl. D15—99

U.S. Cl. D37—1

FIG. 1

FIG. 3

FIG. 2

FIG. 4

FIG. 5

FIG. 1 is a front perspective view of a lapping machine showing my new design;

FIG. 2 is a right hand perspective view of the lapping machine of FIG. 1;

FIG. 3 is a left hand perspective view of the lapping machine of FIG. 1;

FIG. 4 is a top view of the lapping machine of FIG. 1; and

FIG. 5 is a back perspective view of the lapping machine of FIG. 1.

The bottom of the lapping machine is of conventional construction.

I claim:

The ornamental design for a lapping machine, as shown and described.
